UNITED STATES PATENT OFFICE.

KERVIN R. DUNTON, OF BOSTON, MASSACHUSETTS, ASSIGNOR TO DOTEN-DUNTON DESK CO., OF BOSTON, MASSACHUSETTS, A CORPORATION OF MASSACHUSETTS.

DESIGN FOR A DESK.

41,058.

Specification for Design.

Patented Dec. 27, 1910.

Application filed December 15, 1909. Serial No. 533,292. Term of patent 7 years.

To all whom it may concern:

Be it known that I, KERVIN R. DUNTON, a citizen of the United States, residing at Boston, in the county of Suffolk and State of Massachusetts, have invented a new, original, and ornamental Design for a Desk, of which the following is a specification, reference being had to the accompanying drawing, forming a part thereof.

The figure shown is a perspective view of a desk embodying the design.

The ornamental design consists principally in the general lines, shape and formation of the desk whereby an ornamental effect is produced and also in the arrangement of the

ends extending above the plane of the top and in the arrangement of the drawers and handles therefor, together with the ornamental feet, columns, beading and paneling. The top of the desk comprising the writing bed is inclosed between and does not extend beyond the vertical ends of the desk.

I claim—

The ornamental design for desk as shown and described.

KERVIN R. DUNTON.
